UNITED STATES PATENT OFFICE.

EDWARD F. PENDEXTER, OF MILFORD, MASSACHUSETTS.

CAR-COUPING.

SPECIFICATION forming part of Letters Patent No. 645,123, dated March 13, 1900.

Application filed May 2, 1899. Serial No. 715,347. (No model.)

To all whom it may concern:

Be it known that I, EDWARD F. PENDEXTER, of Milford, county of Worcester, and State of Massachusetts, have invented an Improvement in Car-Couplings, of which the following description, in connection with the accompanying drawings, is a specification, like letters on the drawings representing like parts.

10 This invention relates to car-couplings and is intended as an improvement upon the car-coupling shown and described in my United States patent, No. 341,684, dated May 11, 1886.

15 My present invention is embodied in a car-coupling device in which the coöperating draw-heads are provided with hooks which automatically interlock when the cars come together. In the patent referred to the draw-heads have a rotary movement about their longitudinal axes when acting to automatically engage each other, and in my present invention the draw-heads not only have a rotary movement about their longitudinal axes, 20 but in addition thereto a swinging movement in a horizontal plane, said rotary movement of the draw-head being permitted at all times or substantially at all times during the swinging movement thereof. A strap is attached 25 to the draw-bar, which loosely embraces the followers, and said followers are so constructed as to permit the draw-bar to swing laterally and also rotate about its axis, and means are provided on one of the followers which 30

35 limits both the swinging and rotary movement of said draw-bar. The striking-face of the hook of each draw-head has on it a boss, made substantially conical, with its apex at or near the middle of the striking-face, but

40 at one side of the axis of the draw-head. The recess behind the hook is formed with a depression which is adapted to receive the boss on the striking-face of the coöperating draw-head. The draw-bar has formed on its under side a flat-surfaced seat which rests upon a correspondingly flat-surfaced seat on the frame, and as the draw-bar is rotated it is

45 rocked on its seat, yet caused to resume its normal position thereon by gravity. The 50 draw-head is provided with a guard which embraces the hook of the coöperating draw-head; but in this instance said guard is adapted to

assist in rotating the draw-head and is constructed so as to strike the lower end of the coöperating hook when the hook of said draw-head acts upon the upper end of said coöperating hook. A flange is formed or provided at the bottom of the recess back of the hook, which bears against the inclined face or end of the hook of the coöperating draw-head, and thus prevents the draw-heads separating automatically by a movement in a vertical direction, and said flange also assists in separating the draw-heads when one draw-head is turned positively by means provided for the purpose.

Figure 1 shows in plan view an automatic car-coupling device embodying this invention; Fig. 2, a side elevation of the same, the parts being uncoupled; Fig. 3, a front elevation of one of the draw-heads, showing in dotted lines the relative position of the other draw-head when brought into position to engage it; Fig. 4, a similar front elevation of one of the draw-heads rotated on its axis and moved laterally; Fig. 5, a vertical section of one of the draw-heads, taken on the dotted line xx ; Fig. 6, a plan view of the coupling device, the draw-heads being in locking engagement and moved laterally; Figs. 7 and 8, details showing the flat-surfaced seat on the draw-bar and frame in Fig. 7, the draw-bar being in its normal position and in Fig. 8 being rocked; Fig. 9, a detail showing one of the followers; Fig. 10, a detail to be referred to.

The coupling devices of the two cars are precisely alike, and the corresponding parts will be indicated by the same letters, those of one car being distinguished by the accent mark “'”.

The draw-bar $a a'$ has a draw-head $b b'$ at one end, and attached to the opposite end is a loop-like strap $c c'$. The loop-like strap $c c'$ is made more or less elongated and large enough to embrace the followers $d d'$, which are separated by springs $e e'$. The strap $c c'$ embraces said followers loosely in order that the draw-bar may be free to swing laterally in a horizontal plane. That portion 100 of the followers which is embraced by the strap is curved on a radius to the axis of the draw-bar, as represented in Fig. 9, so that the draw-bar is free to rotate about its longi-

tudinal axis. On the rear side of the rear-most follower two lugs $w w'$ project rearwardly, between which the strap $c c'$ is placed, and said lugs serve to limit the lateral and 5 also the rotary movement of the draw-bar. The draw-bar $a a'$ is made cylindrical, and it has formed on it a triangular projection or boss having, essentially, two flat or straight sides or faces at right angles to each other, 10 (see Figs. 7 and 8,) one of which sides or faces is located at the under side of the draw-bar and serves as and constitutes a flat seat $f f'$. The triangular projection is disposed at one side of a vertical line passing through the 15 center of the draw-bar, and when thus disposed the curvature of the cylindrical draw-bar forms a continuation of the flat seat $f f'$ at one side or end thereof, while the opposite side or end of said seat terminates abruptly, 20 and by thus disposing the triangular projection relative to the cylindrical draw-bar it will be seen that said draw-bar can be freely rocked in one direction, but will be restrained from rocking in the opposite direction. 25 The frame supporting the draw-bar $a a'$ has a flat-surfaced seat $g g'$, upon which the seat $f f'$ normally rests, and as the draw-bar swings back and forth the seat $f f'$ is free to slide upon or move along on said seat $g g'$ 30 and is also free to rock on said seat $g g'$ in one direction. The triangular projection is located at the same side of a vertical line passing through the center of the draw-bar that the guard of the draw-head is located, 35 and the hook of said draw-head is located at the opposite side of said vertical line, and as a result the normal tendency is for the draw-head to rest with its seat $f f'$ bearing flat upon the seat $g g'$, and when rocked, as represented in Fig. 8, it will afterward immediately resume its normal position by gravity. 40 The draw-head $b b'$ has a hook $h h'$, with a striking-face formed or provided with a boss $i i'$, (see Figs. 3, 4, and 5,) which is made 45 substantially conical, the apex of the boss being near the middle of said striking-face, but at one side of the axis of the draw-bar. The inclined side $j j'$ of the boss is the principal acting or engaging portion thereof, this 50 inclination being relative to the horizontal plane of the draw-bar. The hook $h h'$ has its end also inclined relative to the vertical plane of the draw-bar, as shown in Figs. 3 and 4. When the two draw-heads come together, the 55 two bosses $i i'$ will strike and will guide and direct the hook $h h'$ into the recesses formed or provided on the draw-heads back of the hooks. When the two draw-heads come together, the upper ends of the hooks, which 60 are made wider than the lower ends, will strike, and each will operate to rotate the other draw-head and also to move the other draw-head more or less laterally. On the 65 back side of the recess behind the hook a depression $y y'$ is formed, (see Fig. 5,) which is of suitable size and shape to receive the boss $i i'$ on the striking-face of the hook. A

guard $k k'$ is provided, which embraces the hook of the other draw-head, and said guard $k k'$ projects forward to a point substantially 70 flush with the striking-face of the hook $h h'$ and is formed and proportioned so that when the two draw-heads come together and the upper ends of the hooks $h h'$ strike each other the lower ends of the guards $k k'$ will at the 75 same time or thereabout strike the lower ends of said hooks, and thereby assist in rotating the draw-heads. In Fig. 3 one of the draw-heads is shown in full lines, the other being represented by dotted lines, and it will 80 be observed that the upper ends of the hooks are in engagement and the lower ends of the guards are in engagement with the lower ends of the hooks.

In order that the heads may turn when 85 their tops are in engagement with each other and their lower ends in engagement with the guards, the said guards are formed with their inner side walls inclined to the vertical plane of the draw-bar, as represented at $v v'$ 90 in Fig. 3. Near the bottom of the recess behind the hook a flange $m m'$ is or may be formed or provided, (see Fig. 5 and dotted lines, Fig. 4,) although in many instances such flange will not be required. This flange $m m'$ 95 bears against the vertically-inclined end of the hook of the other draw-head just above its lower end when the hooks are in locking engagement and prevents the draw-heads from separating automatically in a vertical direction, and said flanges bearing as they do upon the ends of the hooks near their lower ends will assist in rotating the draw-heads when either one of said draw-heads is positively rotated by hand, as shown in Fig. 10. 100

A rock-shaft $n n'$ is provided, which is adapted to be operated by a hand-crank, and said rock-shaft is connected loosely with the draw-head by a link $o o'$, and by turning said shaft n the draw-head will be rotated to disengage 110 the hooks.

I do not desire to limit my invention to the employment of all the features herein shown and described; but with the exception of the flange $m m'$ I prefer to employ all of said features. 115

I claim—

1. In an automatic car-coupling device, a swinging draw-bar capable of rotary movement about its axis having a draw-head provided with a hook to engage the hook of the coöperating draw-head, and having a triangular projection on its under side at one side of a vertical line passing through the center of the draw-bar formed with a flat face to present a seat f, f' , whereby said draw-bar is free to rock in one direction only, and a frame having a seat g, g' on which the seat f, f' rests and upon which the draw-bar is free to slide and rock, substantially as described. 125

2. In an automatic car-coupling device, a swinging draw-bar capable of rotary movement about its axis having a draw-head provided with a hook to engage the hook of the

coöperating draw-head and having a triangular projection at one side of a vertical line passing through the center of the draw-bar which is formed with a flat seat f, f' , one side 5 of which terminates abruptly and the opposite side of which terminates at the curved surface of the cylindrical draw-bar, and a frame having a seat g, g' on which the seat f, f' rests and upon which the draw-bar is 10 free to slide and rock, substantially as described.

3. In an automatic car-coupling device, a swinging draw-bar capable of a rotary movement about its axis having a draw-head, provided with a hook at one side and a guard at the opposite side of the center, and having a projection on its under side which is disposed at the same side of a vertical line passing through the center of the draw-bar as the 20 guard is disposed and having a seat f, f' , said projection permitting the draw-bar to be freely rocked in one direction and restrained from rocking in the opposite direction, and a frame having a seat g, g' on which the seat f, f' rests and upon which the draw-bar is free to 25 slide and rock, substantially as described.

4. In an automatic car-coupling device, a swinging draw-head capable of rotary movement about its axis having a hook h, h' made 30 wider at the upper end than at the lower end, and having its striking-face inclined as at j with relation to the axis of the draw-head, and also having a guard k, k' terminating substantially flush with the striking-face of 35 the hook and having its inner side wall inclined to the vertical plane of the draw-bar, substantially as described.

5. In an automatic car-coupling device, a swinging draw-head capable of a rotary movement about its axis having a hook and a loop-like strap attached to the rear end of the draw-bar, combined with followers embraced by said strap having curved bearing portions 40 for said strap, substantially as described.

45 6. In an automatic car-coupling device, a swinging draw-head capable of rotary movement about its axis having a hook, and a loop-

like strap attached to the rear end of the draw-bar, combined with followers embraced by said strap having curved portions both 50 above and below on a radius to the axis of the draw-bar, substantially as described.

7. In an automatic car-coupling device, a draw-head capable of rotary movement about its axis having a hook, and a loop-like strap 55 attached to said draw-bar, combined with followers loosely embraced by said strap having curved portions permitting rotary movement of the draw-head, substantially as described.

8. In an automatic car-coupling device, a 60 swinging draw-head capable of a rotary movement about its axis having a hook made wider at its upper end than at its lower end, and provided on its striking-face with a substantially-conical boss; the apex of which is 65 at one side of the longitudinal center of the draw-head, substantially as described.

9. In an automatic car-coupling device, a swinging draw-head capable of a rotary movement about its axis, having a hook provided 70 on its striking-face with a boss made substantially conical and having formed in the recess back of said hook a depression to receive the boss on the striking-face of the coöperating draw-head, substantially as described. 75

10. In an automatic car-coupling device, a swinging draw-head capable of a rotary movement about its axis having a hook made wider at the top than at the bottom which engages the top of the hook of the coöperating draw-head, and having a guard terminating substantially flush with the striking-face of the hook, the lower end of which engages the lower end of the hook of the coöperating draw-head to assist in rotating it, substantially as described. 85

In testimony whereof I have signed my name to this specification in the presence of two subscribing witnesses.

EDWARD F. PENDEXTER.
